*Oppenheim & Blanks, and Thomas Blanks
Letters Patent.*

The Schedule referred to in these Letters Patent and making part of the same, containing a description, in the words of the said Oppenheim & and Thomas Blanks, themselves, of their improvement in the manufacture of a composition, which they denominate a Patent Leather paper.

This new and valuable invention essentially consists of the art of making a paper from the surface shavings, or shavings, of leather, which is particularly, and durably fitted for sheathing Weapons; and which is believed to be superior to the sheathing paper, or leather, both of which are now in general use for that purpose. It may also (after suitable preparation) be used for most of the purposes to which leather is applied: As the manufacture of Patent Leather caps, Pocket Books, and for all kinds of Book-Binding. The mode of forming the Patent Leather Paper is similar to that for the manufacture of paper from Rags. The shavings being first ground or beaten to a proper consistency, are put into a suitable mould, from whence they are taken to the press.

The colour of this paper may be varied according to the quality of the shavings used, or by a chemical process. It may be brought to such a degree of fineness, as to be equal to the finest writing paper.

The subscribers claim the sole privilege of using their Patent Leather Paper on the manufacture of any article, to which leather or paper is applied.
